[57] CLAIM

The ornamental design for a paint roller cleaning device, as shown and described.

DESCRIPTION

FIG. 1 is a perspective view of a paint roller cleaning device, showing my new design;

FIG. 2 is an enlarged elevational view of the opposite side thereof;

FIG. 3 is a right end elevational view thereof taken from FIG. 2;

FIG. 4 is a left end elevational view thereof taken from FIG. 2;

FIG. 5 is a bottom plan view thereof;

FIG. 6 is a perspective view of a second embodiment of a paint roller cleaning device.

FIG. 1.

FIG. 2.

FIG. 3.

FIG. 4.

FIG. 5.

FIG. 6.
